(57) **CLAIM**

The ornamental design for an adjustable pant waist system, as shown and described.

DESCRIPTION

FIG. 1 is a front elevational view of the adjustable pant waist system showing the new design with the waist in a wide and closed position.

FIG. 2 is a rear elevational view of the adjustable pant waist system showing the new design with the waist in a wide and closed position.

FIG. 3 is a top view of the adjustable pant waist system showing the new design with the waist in a wide and closed position.

FIG. 4 is a front elevational view of the adjustable pant waist system showing the new design with the waist in a wide and open position.

FIG. 5 is a rear elevational view of the adjustable pant waist system showing the new design with the waist in a wide and open position.

FIG. 6 is a top view of the adjustable pant waist system showing the new design with the waist in a wide and open position.

FIG. 7 is a front elevational view of the adjustable pant waist system showing the new design with the waist in a skinny and closed position.

FIG. 8 is a rear elevational view of the adjustable pant waist system showing the new design with the waist in a skinny and closed position.

FIG. 9 is a top view of the adjustable pant waist system showing the new design with the waist in a skinny and closed position.

FIG. 10 is a front elevational view of the adjustable pant waist system showing the new design with the waist in a skinny and open position.

FIG. 11 is a rear elevational view of the adjustable pant waist system showing the new design with the waist in a skinny and open position; and,

FIG. 12 is a top view of the adjustable pant waist system showing the new design with the waist in a skinny and open position.

(Continued)

The broken lines shown in the drawings depict portions of the adjustable pant waist system that form no part of the claimed design.
